BASKET FOR WASHING MACHINE PARTS

John Andrew Ware, Grain Valley, Mo.

Filed May 9, 1961, Ser. No. 65,082

Term of patent 14 years

(Cl. D49—1)

FIG. 1.

FIG. 2.

FIG. 3.

I claim:

The ornamental design for a basket for washing machine parts, as shown and described.
